UNITED STATES PATENT OFFICE

119,087

DESIGN FOR A COMBINATION CONTAINER FOR SIGNAL FLAG, FUSE, AND TORPEDO

Michael J. Freemark, Breckenridge, Minn.

Application November 18, 1939, Serial No. 88,365

Term of patent 3½ years

To all whom it may concern:

Be it known that I, Michael J. Freemark, a citizen of the United States, residing at Breckenridge, in the county of Wilkin, the State of Minnesota, have invented a new, original, and ornamental Design for a Combination Container for Signal Flag, Fuse, and Torpedo, of which the following is a specification, reference being had to the accompanying drawing, forming part thereof.

The figure is a perspective view of a combination container for signal flag, fuse, and torpedo, showing my new design.

The dominant feature of my design resides in the part shown in solid lines.

I claim:

The ornamental design for a combination container for signal flag, fuse, and torpedo, as shown and described.

MICHAEL J. FREEMARK.
